CONSIN

EXTENSION-TABLE.

1,253,719.

Specification of Letters Patent.

Patented Jan. 15, 1918.

Application filed November 20, 1915. Serial No. 62,522.

To all whom it may concern:

Be it known that we, WILLIAM L. PFEFFERKORN and ALBERT P. SCHLOERB, citizens of the United States, residing at Milwaukee, county of Milwaukee, and State of Wisconsin, have invented new and useful Improvements in Extension-Tables, of which the following is a specification.

Our invention relates to improvements in extension tables.

The object of our invention is to provide means whereby the top of an extension table may be tilted in either the closed or extended position to permit the table to pass through a door-way or to facilitate storing it at one side of a room in such a position that it will occupy minimum space.

In the drawings—

Figure 1 is an end view of an extension table embodying our invention, showing the top in tilted position.

Fig. 2 is a plan view of the same, showing the top in normal position.

Fig. 3 is a fragmentary sectional view, drawn to a plane cutting the hinge pintle transversely and showing a modified form of hinge with fragments of the cap board and tilted bridging board.

Fig. 4 is a view of the hinge shown in Fig. 3 as seen from the under side, together with fragments of the cap board and bridging board.

Fig. 5 is a sectional view, drawn on line $\alpha-\alpha$ of Fig. 2.

Like parts are identified by the same reference characters throughout the several views.

The drawings illustrate our invention as applied to a table of the type known as a pedestal extension table. The pedestal members A, A, are provided with supporting feet A' and with cap boards B. Bridging boards C extend transversely of the table top and normally rest upon the respective cap boards B. Each bridging board is hinged to a pair of guide bars D, D, mounted upon one of the cap boards B, and the hinge connections are so located that the central portion of the bridging board may rest upon the cap board B, from which it is supported between the guide bars D, D. The bridging boards are recessed at C' to permit them to pass between the guide bars. The hinges E are of ordinary type, with one leaf of each hinge secured to one end of a

guide bar D and the other leaf secured to the under surface of the bridging board C in such a position that the recessed portion of the bridging board will register with and receive the guide bars D, when such bridging board is in normal position. These hinges E, however, permit both bridging boards C, C, to be raised from their respective cap boards B and supported from the bars D and hinges E in the tilted position shown in Fig. 1. The pintles of the several hinges are in alinement and in a line which extends longitudinally of the table, parallel with, but offset laterally from, the central longitudinal line of the table.

The tilting movement of the bridging boards is limited by links F, F', which are pivotally connected with each other at f. The link F of each pair is connected with the cap board B by a pivot pin f'. The other link F' of each pair is secured to the corresponding bridging board by a pivot pin F'', the bridging boards being provided with projections C'' to receive the pivot pins f''. The link F may be provided with a bracket stop G to limit the unfolding movement and thereby also limit the tilting movement of the bridging boards.

Extension slides H are mounted upon the bridging boards C in the usual manner. These slides support the table top members I, as in all ordinary extension tables. When the bridging boards are in normal position, the guide bars B are engaged in the recesses C' of the bridging boards, so that when the table top members I, I, are drawn outwardly or pushed inwardly, the pressure is transmitted through the slides to the bridging boards and received by one or the other of the bars B, thereby relieving the hinges from strain. The hinges are sufficiently loose jointed, or the boards C and bars B closely fitted, to allow the bridging boards D to bear upon the bars B without imposing strains upon the hinges.

When the bridging boards are in normal position, the links F, F' will of course occupy the folded position in which they are illustrated in Fig. 2. Each of the bridging boards may be provided with a locking device, such as the turn button J, one end of which may engage underneath one of the bars B at that end which is opposite the one provided with the hinge E. When the button is in holding position, as indi-

cated by dotted lines in Fig. 2, the bridging board cannot be tilted until the button has been swung to an angle of substantially 90° from such position, whereupon it will release the bridging board from the bar B which the button engaged, and this end of the bridging board may then be lifted to tilt the top to the position shown in Fig. 1.

- It will be observed that each cap board 10 B is provided with a pair of bars D. These bars are connected with the cap board by bolts L. When the table is to be transported or shipped from the factory or dealer to place of destination, the bolts L can be removed and the links F, F' disconnected by removing any one of the pivot pins f, f' or f'', whereupon the table top can be removed from the pedestal and crated separately for the purpose of such shipment. If desired, 15 however, the necessity of removing the bolts L may be avoided by employing the type of hinge shown in Figs. 3 and 4, in which views a hinge leaf M, connected with the bridging board, is provided with a hook shaped butt N, adapted to loosely engage around a pintle O, supported at its respective ends from the opposing leaf M', the latter being attached to the bar D. With this 20 construction, the bar D may be so formed as to prevent the hinge members from disengaging, unless the bridging board C is raised to a substantially vertical position. The links F, F' will normally prevent the board from being lifted far enough to permit a release of the member N, but when 25 these links are disengaged, they can be raised to a vertical position and removed.
- We do not limit the scope of our invention to any specific form of hinge connection, nor to any specific form of supporting member. We prefer, however, to make the supporting members in the form of separable pedestal members which include cap plates substantially as illustrated, and guide 30 bars between which the bridging boards will be received when in normal position. By employing the guide bars and by recessing the bridging boards so as to receive the guide bars in the recesses, it is obvious that 35 we may relieve the hinges from all strain due to either lateral or longitudinal pressures against the table, when the bridging boards are in normal position. There will therefore be no pressure upon the hinges, 40 except when the bridging boards are in the raised or tilted position, as shown. The structure of the supporting member or base and the structure of the bridging member or slide support with reference to the question 45 whether these parts are made in separable members or not, is therefore not essential to our invention, since the slides are primarily depended upon to permit a separation of the top boards and to support the 50 top boards in their various positions of ad-

justment. We therefore do not limit the scope of our invention to the use of a plurality of supporting base members nor to the use of a plurality of bridging boards or slide supporting members, although our invention is peculiarly adapted for use in an extension table having separable pedestal members or legs.

We claim—

1. An extension table, including the combination with a set of supporting members, of a set of slide supporting bridging boards in tilting relation to the supporting members and adapted to move with them when the supporting members are separated. 75

2. An extension table, including the combination of a set of separable supporting members provided with cap plates, slide supporting bridging boards mounted upon the respective cap plates and each having hinge connection with said supporting members, said hinge connections being in alignment on an axis extending longitudinally of the table at one side of the center line and adapted to permit the bridging boards to 85 rest flat upon the respective cap plates or to be tilted toward a vertical position at one side of the cap plates. 90

3. An extension table, including the combination of a set of separable supporting members provided with cap plates, slide supporting bridging boards mounted upon the respective cap plates and each having hinge connection with said supporting members, said hinge connections being in alignment on an axis extending longitudinally of the table at one side of the center line and adapted to permit the bridging boards to 95 rest flat upon the respective cap plates or to be tilted toward a vertical position at one side of the cap plates, and link connections 100 between the bridging boards and said supports adapted to limit the tilting movement of said bridging boards. 105

4. An extension table, including the combination of a set of separable supporting members provided with cap plates and having a set of guide bars mounted on each cap plate in a transversely extending position, a set of slide supporting bridging boards, 110 each adapted to rest upon one of the cap plates between the guide bars and having hinge connection with said support adapted to permit the bridging boards to tilt laterally when lifted from between the cap plates and swung upon hinged axes. 115

5. An extension table, including the combination of a set of separable supporting members, a set of bridging boards, each normally interlocked with one of the supporting members in a horizontal position, a connection between each bridging board and its supporting member adapted to permit a tilting movement of the bridging board upon a longitudinal axis parallel with the 120 125 130

longitudinal center line of the table, and means for locking said bridging boards against a tilting movement.

6. An extension table, including the combination of a set of separable supporting members, a set of bridging boards, each normally interlocked with one of the supporting members in a horizontal position, a connection between each bridging board and its supporting member adapted to permit a tilting movement of the bridging board upon a longitudinal axis parallel with the longitudinal center line of the table, and means for locking said bridging boards against a tilting movement, together with means for limiting the tilting movements of the bridging boards when unlocked.

7. An extension table, including the combination of a set of separable supporting members provided with cap plates, a set of guide bars transversely mounted upon each cap plate and detachably connected therewith, a set of slide supporting bridging boards, each mounted upon one of the cap plates and having hinge connection with the guide bar thereon at one side of the cap plate.

8. An extension table, including the combination of a set of separable supporting members provided with cap plates, a set of guide bars transversely mounted upon each cap plate and detachably connected therewith, a set of slide supporting bridging boards, each mounted upon one of the cap plates and having hinge connection with the guide bar thereon at one side of the cap

plate, means for locking said bridging boards against swinging movements on said hinge connections, and folding link connections for limiting the swinging movements of the bridging boards when unlocked. 40

9. An extension table, including the combination of a set of separable supporting members provided with guide members, a set of slide supporting bridging boards, 45 each having hinge connection with one of the supporting members and having recesses to receive said guide members when the bridging boards are in a normally horizontal position, said bridging boards being 50 adapted to be tilted toward a vertical position at one side of the supporting members, when swung upon said hinge connections.

10. An extension table, including the combination of a base, a slide support in hinge 55 connection with the base, slides mounted on the slide support and arranged to move along lines parallel with the axes of the hinge pintles, and separable top boards mounted on the slides, said slide support 60 and base being adapted to interact in normal position to relieve the hinge members from strain when pressure is applied to the table top or base.

In testimony whereof we affix our signatures in the presence of two witnesses. 65
